US0D1061244S

(12) **United States Design Patent** (10) Patent No.: **US D1,061,244 S**
(45) Date of Patent: ** Feb. 11, 2025

(54) DRINK CUP LID	2,050,487 A	8/1936	Durrant
(71) Applicant: Berry Global, Inc. , Evansville, IN (US)	2,120,403 A	6/1938	Godfrey
(72) Inventors: David Y. O'Nan , Henderson, KY (US); David C. Arnold , Evansville, IN (US); Douglas E. Klueh , Evansville, IN (US)	D111,097 S	8/1938	White
	2,174,618 A	10/1939	Burdick
	2,271,589 A	2/1942	Hendrickson
	2,313,801 A	3/1943	Carll
	2,374,092 A	4/1945	Glaser
	D141,225 S	5/1945	Ray
	2,447,407 A	8/1948	Grain
	2,649,984 A	8/1953	Abt
(73) Assignee: Berry Global, Inc. , Evansville, IN (US)	D172,089 S	5/1954	Du Pree
(**) Term: 15 Years	2,766,796 A	10/1956	Tupper
(21) Appl. No.: 29/798,668	2,985,354 A	5/1961	Aldington
(22) Filed: Jul. 9, 2021	3,027,596 A	4/1962	Knowles
(51) LOC (15) Cl. 09-07	3,048,317 A	8/1962	Cochrane
(52) U.S. Cl. USPC D9/447	3,055,540 A	9/1962	Ringlen
(58) Field of Classification Search	3,065,875 A	11/1962	Negoro

(57) **CLAIM**

The ornamental design for a drink cup lid as shown and described.

DESCRIPTION

FIG. 1 is a perspective view of a first embodiment of a drink cup lid showing our new design;

FIG. 2 is a top plan view of the drink cup lid of FIG. 1;

FIG. 3 is a bottom plan view of the drink cup lid of FIG. 1;

FIG. 4 is a right side elevation view of the drink cup lid of FIG. 1;

FIG. 5 is a left side elevation view of the drink cup lid of FIG. 1;

FIG. 6 is a rear elevation view of the drink cup lid of FIG. 1;

FIG. 7 is a front elevation view of the drink cup lid of FIG. 1;

FIG. 8 is a perspective view of a second embodiment of a drink cup lid showing our new design;

FIG. 9 is a top plan view of the drink cup lid of FIG. 8;

FIG. 10 is a bottom plan view of the drink cup lid of FIG. 8;

FIG. 11 is a right side elevation view of the drink cup lid of FIG. 8;

FIG. 12 is a left side elevation view of the drink cup lid of FIG. 8;

FIG. 13 is a rear elevation view of the drink cup lid of FIG. 8;

FIG. 14 is a front elevation view of the drink cup lid of FIG. 8;

FIG. 15 is a perspective view of a third embodiment of a drink cup lid showing our new design;

FIG. 16 is a top plan view of the drink cup lid of FIG. 15;

FIG. 17 is a bottom plan view of the drink cup lid of FIG. 15;

FIG. 18 is a right side elevation view of the drink cup lid of FIG. 15;

FIG. 19 is a left side elevation view of the drink cup lid of FIG. 15;

FIG. 20 is a rear elevation view of the drink cup lid of FIG. 15;

FIG. 21 is a front elevation view of the drink cup lid of FIG. 15;

FIG. 22 is a perspective view of a fourth embodiment of a drink cup lid showing our new design;

FIG. 23 is a top plan view of the drink cup lid of FIG. 22;

FIG. 24 is a bottom plan view of the drink cup lid of FIG. 22;

FIG. 25 is a right side elevation view of the drink cup lid of FIG. 22;

FIG. 26 is a left side elevation view of the drink cup lid of FIG. 22;

FIG. 27 is a rear elevation view of the drink cup lid of FIG. 22;

FIG. 28 is a front elevation view of the drink cup lid of FIG. 22;

FIG. 29 is a perspective view of a fifth embodiment of a drink cup lid showing my new design;

FIG. 30 is a top plan view of the drink cup lid of FIG. 29;

FIG. 31 is a bottom plan view of the drink cup lid of FIG. 29;

FIG. 32 is a right side elevation view of the drink cup lid of FIG. 29;

FIG. 33 is a left side elevation view of the drink cup lid of FIG. 29;

FIG. 34 is a rear elevation view of the drink cup lid of FIG. 29;

FIG. 35 is a front elevation view of the drink cup lid of FIG. 29;

FIG. 36 is a perspective view of a sixth embodiment of a drink cup lid showing my new design;

FIG. 37 is a top plan view of the drink cup lid of FIG. 36;

FIG. 38 is a bottom plan view of the drink cup lid of FIG. 36;

FIG. 39 is a right side elevation view of the drink cup lid of FIG. 36;

FIG. 40 is a left side elevation view of the drink cup lid of FIG. 36;

FIG. 41 is a rear elevation view of the drink cup lid of FIG. 36; and,

FIG. 42 is a front elevation view of the drink cup lid of FIG. 36.

The broken lines are shown for the purpose of illustrating both parts of the article as well as the boundaries of the claim. None of the broken lines form part of the claimed design.
